BIB APRON

Esther N. Hudson, Denver, Colo.

Application August 25, 1945, Serial No. 612,625

2 Claims. (Cl. 2-49)

1

This invention relates to protective garments, primarily for infants and small children, designed for wear over normal garb to safeguard and protect the latter during feeding, certain aspects of play, and like periods of particular soiling hazard, and has as an object to provide an improved such garment.

A further object of the invention is to provide an improved protective garment of bib-apron type designed to entrap and retain spillage otherwise productive of soiling and litter.

A further object of the invention is to provide an improved protective garment of bib-apron type adapted for rapid, convenient, and secure adjustment into positions of use.

A further object of the invention is to provide an improved protective garment of bib-apron type having a lower marginal pocket inherently maintained open in position for use.

A further object of the invention is to provide an improved protective garment of bib-apron type susceptible of rapid and convenient cleaning when soiled.

A further object of the invention is to provide an improved protective garment of bib-apron type that furnishes a maximum of protective cover with a minimum of material and inconvenience to the wearer.

A further object of the invention is to provide an improved construction and interrelation of elements constituting a protective garment of bib-apron type.

A further object of the invention is to provide an improved bib-apron type protective garment that is simple of manufacture, economical of material, efficient in use, and susceptible of practical development in a variety of convenient sizes from any of many suitable materials and an infinity of material patterns.

With the foregoing and other objects in view, my invention consists in the construction, arrangement, and combination of elements herein-after set forth, pointed out in my claims, and illustrated by the accompanying drawing, in which—

Figure 1 is a front elevation of the improved garment as typically mounted and arranged for practical wear. Figure 2 is a three-quarters rear elevation of the garment mounted as shown in Figure 1. Figure 3 is a plan view, on an enlarged scale, of the dismounted garment as developed on the plane of its major element. Figure 4 is a fragmentary, detail section, on a further enlarged scale, taken substantially on the indicated line 4—4 of Figure 3. Figure 5 is a fragmentary,

2

detail view of the pocket-forming element of the garment assembly prior to its incorporation into the completed garment.

In the construction of the improved garment as shown, the numeral 10 designates the major element of the garment wherewith the other garment elements are associated to give effect to the novel concept and principles of the invention; said element 10 being a substantially circular disc of suitable flexible material, such as fabric, coated or uncoated, sheet rubber, and the like, of a size suited to the age or size of the wearer or group for which the finished garment is intended. At any selected point on its peripheral margin, the element 10 is intersected by an outwardly opening notch 11 sized and contoured to closely receive and partially embrace the neck of a wearer, and at a suitable distance from said notch 11, and on each side thereof, a substantially radial slit 12 intersects the element 10 and extends inwardly from the intersected margin thereof towards, but not entirely to, the said element center. As shown in the drawing and above described, the slits 12 converge from opposite sides of the notch 11 inwardly of the element 10 and are spaced apart at their inner ends by an area of uncut material disposed slightly above the center of the element 10 to lie directly below the notch 11 when the garment is mounted for wear, the thus-formed wings of the element 10 defined between each slit 12 and the notch 11 being hence adapted and arranged to overlie and protectively cover forward shoulder portions of the wearer in the manner illustrated by Figure 1 of the drawing.

Stitched or otherwise fixedly secured along its opposed margins to inner margin portions of each slit 12 in the manner shown in Figure 3, a rolled gusset piece 13 closes over and bridges across the slit inner end with a fullness outstanding from the element 10 surface which permits wide separation of the slit margins. Each gusset piece 13 is so shaped as to marginally register with and extend along almost the entire length of the associated slit margin nearest the notch 11, to marginally register with and extend along somewhat less than the inner half length of the slit margin remote from said notch, and to close in secured relation with the element 10 across the inner slit end while outstanding from the element 10 surface as a substantially conical roll whereof the free margin has a length sufficient to bridge between the slit margins when the latter are widely separated and to guard the upper arm of the wearer when the garment is in use. The gusset

piece margins are secured to the associated slit margins by means of superposed, lapped seams wherein the gusset piece and element 10 face surfaces are adjoined to dispose the gusset piece fullness as a roll outstanding from the element 10 and thereby provide a ridge or rib projecting from the surface of the element 10 along each slit 12 margin adjacent the notch 11, which ridges or ribs converge downwardly and centrally of the element 10 when the garment is in position of wear and operate to direct spillage impinging on the element 10 upper portion inwardly and downwardly of said element with protective effect on the apparel wherever the improved garment is mounted.

To form a spillage collecting and retaining pocket on and in operative relation with the improved garment, a straight strip 14, of suitable flexible sheet material the same as or different from that of the element 10, and of suitable length and width, is stiffened and reinforced along one long margin, as by means of a hem, fold, roll, or cord 15, is arcuately tapered at its ends to symmetrically shorten its non-reinforced long margin relative to the reinforced long margin, leaving the latter straight throughout the full extent of its length, and is stitched or otherwise fixedly secured to the element 10 by interconnection of its non-reinforced, end-tapered margin in superposed, marginal registration with the circular margin of said element 10, in the manner and arrangement shown in Figure 3. For considerations of practical use, economy, and convenience it is expedient to form the strip 14 from a length of material of double ultimate strip width folded longitudinally and stitched along a cord 15, in the manner indicated in Figures 4 and 5. The strip 14 is symmetrically arranged marginally of the element 10 with relation to the element diameter bisecting the notch 11 and supplements somewhat more than the lower circular half of said element, the ends of said strip merging with the element circular outline at points uniformly distant from the slit 12 intersections with the element periphery. Due to its conformation and the registration of one of its straight long margins with the circular element outline, the strip 14 defines a pocket whereof the free margin is at all times urged by the stiffness of strip material and the said margin reinforcement to stand away from the adjacent element 10 surface, thereby establishing and maintaining an open recess positioned to receive, collect, and retain crumbs, liquids, and the like, engaging against any portion of the element 10 as normally worn, the converging gusset piece 13 projections functioning to direct spillage against the element 10 upper wings to and for collection with said pocket.

All free margins of the element 10, notch 11, slits 12, and gusset pieces 13 may be tape-finished and bound, if desired, or some or all of said margins, particularly those of the element 10 upper wings, slits 12, and gusset pieces 13, may be left unbound and pinked, as is common practice, both such methods of margin finish being typified in the drawings. As a practicable matter, and to facilitate the provision of garment mounting and securing means, it is desirable to bind the major arc of the element 10 between the slits 12 with a tape 16 and to bind the margin of the notch 11 with a tape 17, in which event end portions 18 of the tape 16 may be extended past the element 10 upper wings to permanent connection with portions of the tape 75

17 projecting just beyond the notch outline, thus providing straps engageable behind and downwardly across the shoulders of the garment wearer which serve to spread and support the outer corners of the garment skirt portion, and tie-strings or tapes 19, which may be extensions of the tape 17 or tape portions 18, are fixed to the junctions of the tape portions 18 with the tape 17 and extend therefrom as free elements 10 connectible behind the neck of the wearer to secure the garment in place. A tape loop 20 may be fixed to the garment margin opposite the notch 11 to provide convenient means for suspending the garment in inverted position from 15 a support for drying, storage, and the like.

The improved garment, constructed and arranged as shown and above described, is a facility of great practical advantage and utility and is particularly noteworthy in respect of the ease 20 and security of its attachment to a wearer, the ever-gaping character of the collecting pocket, and the unique protection deriving from the form, arrangement and operative mounting of the gusset pieces.

25 Since many changes in the specific form, construction, and arrangement of the elements shown and described may be had without departing from the spirit of my invention, I wish to be understood as being limited solely by the scope 30 of the appended claims, rather than by any details of the illustrative showing and foregoing description.

I claim as my invention:

1. A protective garment of the character described, comprising a substantially circular base element of flexible sheet material formed with a marginally-opening, neck-receiving notch, an upwardly and outwardly opening pocket marginally of said base element opposite said notch, 40 a radial slit inwardly intersecting said base element between said notch and each end of said pocket, approximately triangular gusset pieces secured marginally along and in outwardly-rolled, covering relation with inner portions of 45 said slits for extension as maintained inwardly-converging projections beyond the base element surface to bridge the slit inner portions in all slit expansions of garment use, and means for securing said base element to the body of a 50 wearer with the wearer's arms accommodated through said slits.

2. A protective garment of the character described, comprising a substantially circular base element of flexible sheet material formed with 55 a marginally-opening, neck-receiving notch, selectively-connectible flexible ties associated with the opposite corners of said notch, inwardly-converging slits marginally intersecting said base element on opposite sides of and uniformly spaced from said notch, approximately triangular gusset pieces secured marginally along and in outwardly-rolled, covering relation with inner portions of said slits for extension as maintained inwardly-converging projections beyond the base element surface to bridge the slit inner portions in all slit expansions of garment use, flexible straps interconnecting the outer slit corners remote from said notch with the adjacent notch corner tie in free spanning relation 65 with the base element margin between each slit and said notch, and a pocket marginally of said base element opposite and opening toward said notch.

ESTHER N. HUDSON.
